DESIGN FOR A FIRE-PLACE.

Design No. 13,450, dated November 21, 1882.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 13,450, dated November 21, 1882.

Application filed October 17, 1882. Term of patent 7 years.

To all whom it may concern:

Be it known that I, WILLIAM C. PEET, of Jersey City, in the State of New Jersey, have invented a certain new and ornamental Design for Fire-Places, of which the following is a specification.

The design of this fire-place is Moorish, and it is represented in the accompanying engraving. The fire-place frame has columns *a*, supporting the leaflet capitals *b*. There are above this the scroll ornaments *c*, the fret-work *d*, columns *e*, supporting an entablature of leaflet and scroll-leaflet ornaments *f*, as represented. The central recessed portion, *g*, has radial tracery ornaments, and there are ornamental corner-pieces *h*, and a central architrave, *k*, with shield ornament, as shown. The molded cornice *l* surmounts the frame. The fender is made as a colonnade with arches *m*, leaflet ornaments *n*, and a molded cornice, *o*, as shown. The wings of the fender have columns *p* at the corners, a cornice, *q*, and hieroglyphic ornaments *r*, as represented. The back and side plates of the fire-place are ornamented with the arch and leaflet ornaments, as represented at *x*.

I claim as my invention—

1. The design of the fire-place frame, consisting of the columns *a*, capitals *b*, scroll ornaments *c*, columns *e*, fret-work *d*, and an ornamental entablature, substantially as shown. 30
2. The design of the ornamental scroll-work entablature *f*, cornice *l*, architrave *k*, and corner-pieces *h*, substantially as represented.
3. The design of the fender-piece, consisting of the colonnade *m*, scroll-leaflet ornaments, 35 and cornice *o*, substantially as shown.
4. The design of the fender-wings, consisting of the corner-columns, cornice, and hieroglyphic ornaments, as represented.

5. The design of the arch and leaflet ornaments for the side plates, as represented. 40

Signed by me this 13th day of October, A. D. 1882.

WILLIAM C. PEET.

Witnesses:

WILLIAM G. MOTT,
